UNITED STATES PATENT OFFICE

HARRY E. NORVIEL, OF ANDERSON, INDIANA, ASSIGNOR TO DELCO-REMY CORPORATION, OF ANDERSON, INDIANA, A CORPORATION OF DELAWARE

SWITCH

Application filed April 8, 1929. Serial No. 353,311.

This invention relates to electric switches in combination with an ignition coil, and one of the objects is to provide a novel and simple means of controlling the circuits through the ignition coil in conjunction with certain registering or indicating circuits so that a key controlled device will simultaneously operate to open and close all of the circuits and to secure them in open relation.

10 A further object of the invention is to provide a unit of structure which includes in addition to the key controlled means for securing the ignition circuit in open position, means for opening and closing the circuit of an electrical register and coincidentally securing the same in open relation with the ignition circuit.

In the present invention these aims are accomplished by providing an electric switch 20 in which a movable contact element is a leaf spring conductor fixed at an intermediate point to one of the ignition terminals of the coil and having the bowed free ends thereof adapted to engage a convex surface provided by suitable stationary contacts. A movable actuating member presses each end of the contact blade against the stationary contacts, one of which is a second ignition contact and the other a contact of said register circuit.

25 Further objects and advantages of the present invention will be apparent from the following description, reference being had to the accompanying drawing wherein a preferred embodiment of one form of the present invention is clearly shown.

In the drawing:

Fig. 1 is a longitudinal section through a switch and coil unit embodying my invention, and is a view substantially along the line and 40 in the direction of the arrows 1-1 of Fig. 3.

Fig. 2 is a rear view of the unit as indicated by the arrow 2 of Fig. 1.

Fig. 3 is a sectional view through the switch mechanism of the unit substantially as indicated by the line and arrows 3-3 of Fig. 1.

Fig. 4 is a front view of the unit as indicated by the arrow 4 of Fig. 1, the dial plate and bezel ring being removed and the unit being rotated substantially through an angle 50 of 90°.

Fig. 5 is a longitudinal sectional view through the contact actuator assembly, substantially as indicated by the line and arrows 5-5 of Fig. 1.

Fig. 6 is a diagrammatic view of the electrical circuit through my improved switch and coil unit.

With particular references to the drawing, 20 indicates a case enclosing an ignition coil and is attached to a sleeve 21 secured to a mounting bracket 22, which sleeve 21 has an interfitting relation with a metallic end wall or frame member 23 completing a switch housing and supporting a key controlled actuator for a switch mechanism later to be described. The case 20 is flanged at 24 to receive a nonconducting member 25, forming a switch base and providing an end wall of the ignition coil housing. The non-conducting member 25 is provided with a skirt 26 70 positioning a block 27 centrally recessed at 28 within which is received one end of a core 29. About the core are superimposed a secondary winding 30, and a primary winding 31 the other end of the core 29 being supported by a skirt 32 of the coil cap 33 which is secured to the case 20 by an interlocking joint 34. Within the case 20 and about the coil windings there is provided a magnetic winding 35 which is grounded to the case 20 in the usual manner.

The coil cap 33 is of molded formation and secures within the body thereof a high tension terminal 40 which has connection by a pin 41 with the core 29 of the coil and thence to the inside turn of the secondary winding. The cap also moldably secures a battery terminal post 42, a gas gage terminal 43 and a timer terminal 44, which have appropriate connections to and through the ignition coil to complementary terminal members moldably secured to the member 25. The non-conducting member 25 supports terminal members 50, 51 and 52 which form the elements of a switch mechanism as will presently appear. The member 50 is connected by a wire 53 with the gas gage terminal 43 while the terminal member 51 is connected by a lead 54 with the terminal post 42 and the terminal member 52 by a wire 55 to the inside lead of 100

the primary and the outside of the secondary, and from thence by way of the primary 31 and outside lead 56 thereof to the post 44, and also from thence by way of the secondary windings to the core 29.

5 To the terminal member 51 there is secured an arc shaped spring leaf contact blade 60 which is crimped into a rather sinuous formation as shown in Fig. 1, so that the concave free ends 61 and 62 lie over the terminal members 50 and 52 respectively, but are normally spaced therefrom or out of contact therewith.

10 The frame member 23 supports a key cylinder 65 carrying bolts 66 which cooperate with a key 67 to permit the key cylinder 65 to be rotated within the frame. A stop post 68 formed upon the frame member 23 adjacent the inner end of the key cylinder 65 acts as 15 a stop and defines the limits of rotation of the cylinder. To the inner end of the key cylinder 65 is secured a contact actuator mechanism by screws 69 driven through a nonconducting ratchet plate 70 and a supporting 20 plate 71. The plates 70 and 71 are somewhat arc or crescent shaped as exhibited in Fig. 3, and provide arms 72 and 73, which in assembled relation cooperate with the contact arms 61 and 62 to complete the circuits 25 through the member 51 and the members 50 and 52. The arms of the member 70 are of such dimension that junctures 74 and 75 operate as stops in conjunction with the post 68 to limit the rotary movement of the contact 30 actuator. The intermediate portion of the members 70 and 71 are apertured at 76 and 77 to provide detent recesses to cooperate with the spring 78 and ratchet ball 79 secured within the frame member 23 temporarily retaining 35 the actuator device in the actuated position to which it may be moved.

40 When the frame and contact actuator assembly are assembled with the sleeve 21, the tangs 80 of the said sleeve are bent into recesses 81 about the periphery of the frame 23 and the switch actuating arms 72 and 73 are disposed in a relative position exhibited in Fig. 3, in which the switch parts are arranged in the off position. A face plate 90 45 and a dial plate 91 are then placed over the frame 23 and secured by screws 93 and finished off by bezel ring 94.

50 The unit herein above described is complete in itself and is adapted for mounting 55 upon any substantial part of the vehicle structure after which the high tension terminal 40 may be connected with the usual distributor 100, the terminal post 42 with the battery 101 and thence grounded at 102, the terminal 43 is then connected with the gas gage 103 by a conductor 104 and thence grounded at 105, and the terminal 44 is connected to the timer 106, thence to the ground 60 107 as illustrated in Fig. 6.

65 Whenever the switch is manipulated to

open or close the various circuits, the contact elements 61 and 62 are caused to rub over the respective terminal members 50 and 52 by reason of the arms 72 and 73. In forcing the elements 61 and 62 into engagement with 70 the contacts 50 and 52, the arms 72 and 73 will iron out the concave bends 61 and 62 and in doing so will cause the free ends of the member 60 to slide over the convex parts 50 and 52. It is to be noted that the terminal 75 51 forms a common terminal with the coil circuit through the terminal 52 and with the registering circuit through the terminal 50, and that when the plate 70 is rotated that 80 these circuits are opened and closed coincidentally. Closing of the coil circuit thereby establishes a closed registering circuit by which the indicia may be read off. Since the registering circuit functions only when the coil circuit functions, danger of battery depletion is reduced to a minimum, for when the coil circuit is opened the registering circuit is likewise opened thus being no drag upon the battery while the vehicle is at rest.

85 While the form of embodiment of the present invention as herein disclosed, constitutes a preferred form, it is to be understood that other forms might be adopted, all coming within the scope of the claims which follow.

90 What is claimed is as follows:

1. A switch comprising three terminals arranged in a row, a spring metal conductor attached intermediate its ends to the center terminal, and having its free ends located so as to engage respectively the other terminals, 100 and means for causing the ends of the spring conductor to simultaneously engage said other terminals, said means comprising a movable member having blades so constructed and arranged that, when the movable member is in the "off" position, one of the blades will be positioned intermediate the ends of the spring conductor and the other blade will be located beyond the end of said spring conductor.

105 2. A switch comprising three terminals arranged in a circular row, a spring metal conductor attached intermediate its ends to the center terminal, and having its free ends located so as to engage respectively the other terminals, and means for causing the ends of the spring conductor to simultaneously engage said other terminals, said means comprising a rotatable member having blades pivoted at the axis of said circular row of contacts, and so arranged that, when the movable member is in the "off" position, one of the blades will be positioned intermediate the ends of the spring conductor and the other blade will be located beyond the end of said spring conductor.

110 3. A switch comprising three terminals arranged in a circular row, a spring metal conductor attached intermediate its ends to the center terminal, and having its free ends lo-

cated so as to engage respectively the other terminals, and means for causing the ends of the spring conductor to simultaneously engage said other terminals, said means comprising a rotatable shaft journalled for rotation at the axis of said circular row of contacts, and a switch actuator carried by the shaft having blades so constructed and arranged that, when the actuator is in the "off" position, one of the blades will be positioned intermediate the ends of the spring conductor and the other blade will be located beyond the end of the spring conductor, said spring conductor being arc-shaped and substantially concentric with the shaft.

In testimony whereof I hereto affix my signature.

HARRY E. NORVIEL.
